[57] CLAIM

The ornamental design for a remote control unit, as shown and described.

DESCRIPTION

FIG. 1 is a perspective view of the remote control unit embodying our design;

FIG. 2 is a side elevational view of the remote control unit as shown in FIG. 1, the opposite side elevational view being a mirror image thereof;

FIG. 3 is an end elevational view of the remote control unit as shown in FIG. 1;

FIG. 4 is an opposite end elevational view of the remote control unit as shown in FIG. 1;

FIG. 5 is a top plan view of the remote control unit as shown in FIG. 1; and,

FIG. 6 is a bottom plan view of the remote control unit as shown in FIG. 1.

FIG. 1

FIG. 2

FIG. 3
